METAL FENCEPOST

Filed April 17, 1919

UNITED STATES PATENT OFFICE.

RAYMOND C. KNOPKE, OF WHEATON, ILLINOIS.

METAL FENCEPOST.

Application filed April 17, 1919. Serial No. 290,816.

To all whom it may concern:

Be it known that I, RAYMOND C. KNOPKE, a citizen of the United States, and a resident of Wheaton, county of Du Page, and 5 State of Illinois, have invented certain new and useful Improvements in Metal Fenceposts, of which the following is a specification.

My invention relates generally to improvements in fence posts, but relates more particularly to improvements in metal fence posts of the type generally used for supporting wire fencing.

In wire fences a considerable upward 15 pull is exerted upon the post, particularly upon those posts which are placed in the valleys or depressions. It is of course important that the post resist any such upward pull and that it be anchored firmly 20 in place against all forces tending to remove it.

The general object of my invention is to provide a metallic post which shall serve as a proper support for the wiring or fencing; that shall be adapted to be driven into the ground without the necessity of first providing a post hole; that when so driven shall be firmly anchored in place and shall effectually resist forces tending to displace 30 or remove the same; and which shall have the anchoring means so formed that relatively thin-gage metal shall be sufficient to withstand the tremendous forces to which it is subjected when being driven into the 35 ground.

My invention consists generally in the form, arrangement, construction and cooperation of the parts whereby the above named objects, together with others that 40 will appear hereinafter, are attainable and my invention will be more readily understood by reference to the accompanying drawings wherein I have illustrated that embodiment of my invention which I consider 45 to be the best at the present time.

In said drawings: Fig. 1 is a vertical elevation of a section or portion of fencing containing metallic posts embodying my invention. Fig. 2 is an enlarged elevation of the lower part of the post showing the construction of the anchor. Fig. 3 is a sectional view substantially on the line 3—3 of Fig. 2. Fig. 4 is a sectional view of the anchor substantially on the line 50 4—4 of Fig. 2. Fig. 5 is a view similar to Fig. 3, but illustrating the post and an-

chor positioned in the soil or earth. Fig. 6 is a face view of a modified form of anchor plate embodying my invention, and Fig. 7 is a sectional view substantially on 60 the line 7—7 of Fig. 6.

In Fig. 1, I have shown two posts, 1, as they appear looking at the face thereof when driven into the ground or earth, 2. Upon the posts 1, and suitably supported 65 thereby will be found the fencing material 3, which in the present instance is indicated as the ordinary barbed wire fencing, but which obviously may be wires of other forms or wire netting to fit the particular 70 requirements.

The particular character of the body of the post does not form a part of the invention and it will not therefore be described in detail. I wish to state, however, that I 75 prefer to use a metal post of T or L shape in cross section; the construction of the post proper being such as will yield the greatest strength with the use of the least metal. The amount of the metal required is a large 80 item which will be understood from the fact that posts of this kind are used by the millions and that a relatively small saving in a single post in the aggregate is of great 85 moment.

It is with respect to the anchor plate 4 that my invention is particularly concerned and wherein I have provided a novel structure which serves effectually to hold or anchor the post in the ground and which at 90 the same time is so formed as to permit driving of the post into the ground without the necessity of first forming or digging a post hole. I have so designed the anchor plate that very thin gauge metal may be 95 utilized and at the same time furnish the strength requisite to withstand the displacing, bending and deforming action met with when the post is driven into ground. The anchor plate 4 is provided with side cutting edges 5 and 6, with a bottom cutting edge 7, and with a top edge 8. The form that the side bottom cutting edges takes may be varied to a considerable extent and the form shown in Figs. 1 and 2 is of the form 100 disclosed in my Patent No. 1,237,654 of August 21, 1917. The plate 4, in that form disclosed in Figs. 1 to 5 inclusive is provided with integrally offset portions 9, 10, 11 and 12, the portions 9 and 10 being upon 110 opposite sides of the post 1 and the portion 9 being formed or bumped inwardly

and the portion 10 outwardly. The portion 11 is bumped outwardly in the present instance and the portion 12 is bumped or formed inwardly. By this disposition of 5 the offset portions and the forming of certain portions thereof outwardly and others thereof inwardly, an arrangement is provided which enables the post to be driven into the earth straight, since the various 10 forces tending to change the course of the post are neutralized. These offset portions 9, 10, 11 and 12 are preferably gently curved from the plane of the face of the plate, so that they may offer but a minimum of resistance when the post is driven into the 15 earth. After the post is driven into the earth and has remained there for a short time, the earth naturally finds its way into the various pockets or recesses formed by 20 the offset portions and packs into place in a manner that forms a very powerful anchorage such as will resist any upward, as well as downward strains to which the post in practice is subjected

25 The offset portions 9, 10, 11 and 12 serve another very important and useful function and that is, by way of strengthening the anchor plate 4 and making it into such a rigid form that even a relatively thin plate 30 suffices to withstand twisting, bending and other forces imposed upon the plate in service. The offset portions are also preferably of arcuate or curved form to the end that the maximum of strength may be realized by the bulge or offset formation and to 35 the end that a gentle undulatory surface may result, which will offer a minimum of resistance to the passage of the plate when being driven into the ground.

40 I wish it to be understood, however, that the anchor plate need not necessarily be formed as shown in Figs. 1 to 5 inclusive, and that the number, shape and disposition 45 of the offset portions may be varied. Thus in Figs. 6 and 7 I have shown an anchor plate 13, which is provided with two offset portions 14 and 15 that are substantially of triangular form, starting from a point 16 at one offset portion and at a point 17 50 at the other, which is in the same plane as the general plane of the plate and which extend at a slight angle outwardly, thus forming two somewhat conical-shaped pockets. The anchor plate proper in this instance is also of slightly different form, being merely triangular in shape. This construction is one which permits the anchor plate to be readily driven into the ground 55 because of the pointed construction of the offset portions or pockets and which at the same time serve as a powerful anchorage to hold the post in place against all forces tending to raise or displace the same. Obviously the offset or outwardly formed por-

tions being within the general confines of the edge portions of the anchor also serve admirably to strengthen and reinforce the plate and thus enable the successful use of a relatively light plate. As before stated, although but little metal may be saved 65 in any single post or anchor, the aggregate saving as covered in the production of millions of posts is very large indeed. 70

After the post has been driven into the ground, the soil or earth which has been 75 somewhat loosened or displaced by the anchor in its movement through the earth, finds its way into and becomes hard packed around the anchor and particularly in the pocket portions thereof. 80

The offset portions are all within the confines of the edge portions of the anchorage and they do not therefor, in any way affect the cutting functions of said edges. On the other hand the offset portions are preferably 85 brought relatively close to the edges of the plate between the edge portions thereof and the offset portions, even when a very thin plate is used.

Again the plate, while it is formed with 90 offset portions is not in any wise cut or sheared so that its inherent strength as an integral piece is not weakened.

The simple, durable and relatively inexpensive construction of the post herein 95 shown and described will be apparent to those skilled in the art without further comment.

I claim:—

1. In combination, a post and an anchor 100 plate secured thereto, said plate having a struck up strengthening rib thereon extending outwardly from the plane of the plate on one side thereby forming a depression upon the opposite side, said rib being joined 105 throughout to the remainder of the plate.

2. In combination, a post and an anchor plate secured thereto, said plate having a struck up strengthening rib thereon, the longitudinal axis of said rib extending 110 transversely of the post, said rib extending outwardly from the plane of the plate on one side, thus forming a depression upon the opposite side, and said rib being joined throughout to the remainder of the plate. 115

3. In combination, a post and an anchor plate secured thereto, said anchor plate being provided with cutting side and top edges and having a struck up strengthening rib thereon and within the confines of said edges, said rib extending outwardly from the plane of the plate on one side, thus forming a depression upon the opposite side, and said rib being joined throughout to the remainder of the plate. 120

In testimony whereof, I have hereunto set my hand this 31st day of March, 1919.

RAYMOND C. KNOPKE
